UNITED STATES PATENT OFFICE.

FREDERICK WESTERBECK, OF ST. LOUIS, MISSOURI.

SHEET-METAL CAN.

1,347,665.

Specification of Letters Patent. Patented July 27, 1920.

Application filed April 30, 1915. Serial No. 24,866.

To all whom it may concern:

Be it known that I, FREDERICK WESTERBECK, a citizen of the United States of America, a resident of the city of St. Louis, State 5 of Missouri, have invented certain new and useful Improvements in Sheet-Metal Cans, of which the following is a full, clear, and exact description, reference being had to the accompanying drawing, forming a part of 10 this specification.

My invention relates to improvements in sheet metal cans, one of the objects being to produce a very strong can which is made of extremely thin sheet metal. By bending 15 the sheet metal in a particular manner, as will be hereinafter described, I produce reinforcing elements which very effectively strengthen the closure and can body, so that these parts may be made of very light and 20 inexpensive sheet metal.

Another object is to produce a can body having flattened closure seats which very firmly engage a large area of the closure. A further object is to provide an improved 25 means for retaining the closure on the can body.

Figure I is a side elevation, partly in section, illustrating a sheet metal can embodying the features of my invention.

Fig. II is a top or plan view of a portion 30 of the can.

Fig. III is an enlarged vertical section taken on line III—III, Fig. I.

Fig. IV is an enlarged vertical section 35 taken on line IV—IV, Fig. I, the closure being omitted.

A designates a can body, and B designates a closure fitted to said body. The can body is made of sheet metal, and its upper portion 40 is turned inwardly at 1, downwardly at 2, outwardly at 3, and upwardly at 4. By bending the sheet metal in this manner, I produce an inturned oblong bead adapted to receive the closure B. This bead is 45 flattened at 2 and 5 to produce flattened closure seats which firmly engage a very large area of the closure, the object being to produce a substantially air tight can. The upturned marginal portion 4 of the metal of 50 the bead terminates in a raw edge which lies between the flattened closure seats, and this upturned portion constitutes a reinforcing element for strengthening the can. The oblong bead is so formed that the raw edge of 55 the metal lies adjacent to the flattened outer closure seat 5 as shown in Fig. IV, and

when the closure is applied to the can, said raw edge is firmly forced into engagement with the metal of the closure seat 5 as seen in Fig. III, thereby rendering the bead very 60 rigid, and very strong.

The closure is provided with a depending annular flange 7 which is flattened to engage the flattened closure seat 5, a substantially semi-circular marginal portion 8 which extends from the flange 5 to a depending web 9, the latter being flattened to engage the closure seat 2. The substantially semi-circular portion 8 engages a correspondingly shaped portion of the oblong bead at the 70 upper edge of the can. The web 9 extends downwardly from the inner face of the oblong bead, and the lower edge of said web 9 is integrally connected to an inclined web 10 which extends toward the center of the 75 can and terminates at the flat center web 11.

The inner lower corner of the oblong bead is curved as seen at 12, and the closure web 9 is pressed outwardly to form detents 13 (Figs. II and III) which engage said curved 80 corner. Each detent 13 is provided with a curved shoulder which engages the curved corner 12, and also provided with an inclined face which extends downwardly and inwardly from said shoulder. In applying the 85 closure to the bead, the inclined faces of the detents 13 are forced to the position shown in Fig. III the bead will spring to the position illustrated so as to retain the closure on the can. 90

The closure is reinforced by pressing the metal as shown most clearly in Fig. III, and also by folding the flange 7 backwardly on itself to provide a double thickness of metal at the outer margin of the closure. 95

Indentations 15 are formed in a can body to produce shoulders 16 which are adapted to receive a closure removing device. The closure flange 7 engages the can body at points above the shoulders 16, and the folded 100 edge of this flange 7 lies adjacent to said shoulders 16 so that a knife or other suitable implement may be inserted between a shoulder 16 and the folded edge of the flange 7 for the purpose of removing the closure. 105 Since the closure removing device engages the lower edge of the flange 7 it is an advantage to fold said flange as shown in Fig. III. If the extremely thin sheet metal were not folded at this point, it would readily 110 tear and bend during the operation of removing the closure.

I claim:—

1. A sheet metal can comprising a body member having its upper portion turned inwardly, downwardly and outwardly to produce a yieldable bead, the metal at the lower inner corner of the bead being curved, and a closure fitted to the inner and outer faces of said bead, said closure being provided with an annular web which extends downwardly from the inner face of the bead and said web being pressed outwardly to produce detents each of which is provided with a shoulder adapted to engage said curved corner of the bead.
- 10 2. A sheet metal can comprising a body member having its upper portion turned in-

wardly, downwardly and outwardly to produce a yieldable bead, the metal at the lower inner corner of the bead being curved, and a closure fitted to the inner and outer faces of said bead, said closure being provided with 20 an annular web which extends downwardly from the inner face of the bead and said web being pressed outwardly to produce detents each of which is provided with a shoulder adapted to engage said curved 25 corner of the bead, each of said detents also having an inclined face which extends downwardly and inwardly from said shoulder.

FREDERICK WESTERBECK.
